UNITED STATES PATENT OFFICE.

JOSEPH KRÜCKELS, OF ZELL-IM-WIESENTHAL, GERMANY, ASSIGNOR TO THE FIRM
MASCHINENFABRIK ZELL, J. KRÜCKELS, OF ZELL-IM-WIESENTHAL, GERMANY.

CREEL STAND.

Application filed September 21, 1926, Serial No. 136,863, and in Germany September 23, 1925.

In the creel stands hitherto known for warping from stationary creels (conical cross-wound bobbins come principally into consideration) the drawing off of the thread takes place usually in the horizontal direction or nearly so. This has the disadvantage that the thread as it is drawn off in consequence of its own weight, rubs the upper edge of the bobbin more strongly than the lower. Besides causing the formation of waste the thread is not uniformly pulled, but sometimes stronger and at the next moment less. Another disadvantage of this hitherto usual arrangement of horizontally placed bobbins arises from the difficulty of replenishing the frame work with full bobbins. The accessibility of the creel holders is hindered by the framework stretching the threads. It is true that the German Patent No. 276,602 tries to overcome this disadvantage by moving out the framework stretching the thread and the German Patent No. 352,713 arranges the inner frame of creel holder to be movable, but these arrangements make a more complicated and consequently more expensive construction of machine necessary. Attempts have been made to place the axis of the creels vertically, but then the disadvantage shows itself that the room required for a creel stand of this kind is considerably greater and the service especially when large sized cross bobbins are used becomes complicated and the possibility of using the frame practically becomes questionable.

According to the present improvement these disadvantages are avoided by arrang-

ing the creels alternately standing and hanging whilst they are placed with their axes vertical or substantially vertical. Retarding thread guides are placed between them and so utilize the space fully and make a compact construction possible. The creels and the thread guides are readily accessible so that replenishing the frames with new creels and the tying of threads can be readily effected.

The drawing illustrates a detailed example of the framework according to my invention:

Fig. 1 shows the creel holder as seen from the side,

Fig. 2 shows its ground plan.

The stationary creels 1 rest upon or hang from the horizontal beams 2 which also carry the retarding thread guides 3. These thread guides 3 pass the single yarn threads forward in the known way to the thread collectors 4, whence they pass on to the warping machine. This arrangement of alternate standing and hanging creels with the thread guides between them makes a considerable saving of space possible. If desired the creels can be arranged slightly out of the vertical without departing from the invention.

I claim:

A creel stand for warping from stationary creels in which the shuttles are arranged with vertical axes alternately standing and hanging with retarding thread guides between them.

In testimony whereof I affix my signature.

JOSEPH KRÜCKELS.
